UNITED STATES PATENT OFFICE.

CHARLES E. HITCHINGS, OF NEW YORK, N. Y.

ROCKING GRATE.

SPECIFICATION forming part of Letters Patent No. 416,332, dated December 3, 1889.

Application filed April 5, 1889. Serial No. 306,103. (No model.)

To all whom it may concern:

Be it known that I, CHARLES E. HITCHINGS, of the city, county, and State of New York, have invented a certain new and useful Improvement in Rocking Grates, of which the following is a specification.

I will describe a rocking grate embodying my improvement in detail, and then point out the novel features in the claim.

10 In the accompanying drawings, Figure 1 is a plan or top view of a rocking grate embodying my improvement. Fig. 2 is a front elevation of a base-piece in which my improved grate is contained and showing certain means 15 for shaking the grate-bars. Fig. 3 is a sectional view taken on the line xx , Fig. 1. Fig. 4 is a sectional view taken on the line yy , Fig. 1.

Similar letters of reference designate corresponding parts in all the figures.

A designates a base or chamber in which the grate-bars are arranged, and a a frame in which the grate-bars are journaled at one of their ends. The base A comprises an ash-pit 25 a' below the grate-bars, and is provided at its front with a door a^2 , through which ashes may be removed. This base may be applied to a furnace, stove, boiler, or other heating appliances.

30 The frame a , in which the rocking grate-bars are partially journaled, comprises a plate-like rim which may be set down upon the interior of the base and will rest upon an internally-extending flange a^3 , formed in the base and passing about the same near its upper side.

The forms of the grate-bars are immaterial; but I have illustrated a form comprising longitudinally-extending ribs a^4 and diagonally-extending branches or projections a^5 . Each 40 of the grate-bars, near its ends, is provided

with journals a^6 a^7 , which are made integral therewith. The journals a^6 extend into bearings a^8 , formed upon the under side of the frame a . In fact, the bearings a^8 may be cast integral with the frame a . The journals a^7 of the grate-sections extend through bearings a^9 , formed in the base A at the front thereof. From the upper sides of the grate-bars, when the said sections are in operative position, 45 there extend upwardly projections a^{10} , constituting stops which prevent longitudinal displacement of the grate-bars, for the reason that

if such longitudinal movement is attempted the said stops will contact with the adjacent edges of the frame a , and thus prevent the said 55 movement of the bars.

In order to introduce the grate-bars into the base and secure them in position, they are passed in through the opening of the door a^2 , with the stops a^{10} inverted or turned downwardly. In such position the journals a^7 of the grate-bars are passed through their bearings a^9 far enough to admit of the journals a^6 being passed backwardly through the bearings a^8 . When the journals are properly withdrawn in their bearings, the grate-bars are rotated so as to bring the stops a^{10} upon the upper sides of the grate-sections and into their normal position.

The outer ends of the journals a^7 of the 70 grate-bars extend through the base A and there are secured to said outer ends arms a^{11} , which arms, in this instance, extend upwardly. I have shown a convenient means for securing the arms to the outer ends of the 75 journals, consisting of squaring the outer ends of the journals and passing them through correspondingly-shaped apertures in the lower extremities of the arms a^{11} . When in such position, the arms a^{11} may be secured, so as to prevent their accidental displacement, by means of set-screws a^{12} . (Shown more clearly in Fig. 2.) The upper ends of the arms a^{11} have a 80 pivotal connection with a connecting-rod a^{13} . This connecting-rod operates, when moved longitudinally, to cause the rocking of all the arms a^{11} in unison, and the latter, by their connections with the journals of the grate-bars, will thus cause the rocking of the grate-bars. The rod a^{13} may be moved in both directions, 85 and thus cause a shaking movement of all the grate-bars.

I have shown upon certain of the arms a^{11} sockets a^{14} , into which sockets may be inserted a handle or handles of any suitable kind for 90 causing the movement of the rod a^{13} and the rocking of the grate-sections.

It is to be particularly observed that the arms a^{11} extend upwardly from the journals of the grate-sections, and are therefore in such 100 position that they do not interfere with the opening or closing of the ash-pit door a^2 . It is to be observed, also, that by forming the bearings for the journals a^6 a^7 integral with the

base A, or an appurtenance thereof, all use of bolts or rivets in the forming of the bearings is avoided, and by forming the journals a^6 a^7 integral with the grate-bars the use of all sockets or independent shanks is dispensed with. Although I have shown the said bearings as formed one upon the frame a and another within the base, it is quite obvious that the bearings might be formed wholly within the base or upon the frame, as is desired, as the frame merely constitutes a portion or appurtenance of the base.

What I claim as my invention, and desire to secure by Letters Patent, is—

The combination, with a base, of rocking grate-bars having both their journals formed integral therewith, and their forward journals projecting through the front of the base, bearings for said journals formed integral with the base or an appurtenance thereof, said grate-bars being provided upon their upper sides with stops for preventing the longitudinal movement of the bars when in their normal position, substantially as specified.

CHARLES E. HITCHINGS.
